CLAIM

The ornamental design for cookware lid, as shown and described.

DESCRIPTION

FIG. 1 is a top, front, right side perspective view of a cookware lid;

FIG. 2 is bottom, front, right side perspective view thereof; FIG. 3 is a front elevation view thereof, the rear elevation view being a mirror image;

FIG. 4 is a left side elevation view thereof, the right side elevation view being a mirror image;

FIG. 5 is a top plan view thereof;

FIG. 6 is a bottom plan view thereof; and,

FIG. 7 is a vertical cross-section view thereof, taken along Line 7-7 of FIG. 4.

(Continued)

In the drawings, the broken lines are for the purpose of illustrating environment only, and form no part of the claimed design.
